UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

METALLIC STRUCTURE FOR RAILWAY CARS.

Original application filed October 19, 1922, Serial No. 595,634. Divided and this application filed September 8, 1925. Serial No. 55,207.

My invention relates to the construction of railway cars and more particularly to metal end structures or walls for railway car made of one or more metallic plates or panels 5 formed with integral reinforcing, stiffening and bracing corrugations or embossments. However, this device may be incorporated in the construction of car side walls, floors, roofs or doors used in connection with railway cars 10 of various types.

It is well known that the end walls of railway cars are more likely to be broken or otherwise injured than the side walls. This is due to the inertia thrusts and pressures 15 caused by the shifting of the cargoes when the train starts or stops. These thrusts may be local, tending to distort the end in some particular spot, as, for example, when a piece of piping or lumber shifts lengthwise imparting a blow against the end wall of the car; or there may be a general tendency to break 20 out the end wall as a whole or tear it away from the framing. For the purpose, therefore, of greater strength and durability, car 25 ends have been constructed of metal plates corrugated or formed with ribs to impart the desired strength, rigidity and resiliency.

One of the principal objects of my invention is to provide a corrugated or embossed 30 metallic end structure for railway cars in which the corrugations or embossments have a configuration and arrangement that impart to the structure a maximum capacity for resisting cargo thrusts, both local and general, 35 static or quiescent, and with sufficient resiliency to prevent permanent distortion due to the thrusts of the loads, with a minimum weight of metal. It is important that structures of this sort should be as light as is possible, consistent with strength and durability, 40 both for reasons of economy in manufacturing cost and also to keep the weight of the car at a minimum.

A further object is to provide a corrugated metallic wall element that is practically possible to manufacture. A further object is to provide a metallic wall element with corrugations or embossments that resist to a greater degree torsional stresses, as well as brace

the element, and the car end against diagonal 50 side thrusts or weaving.

Like characters of reference designate like parts. 90

The end wall structure shown in the above figures comprises a panel composed of a corrugated metal plate or plates.

Referring to Figs. 1 and 2, the corrugated plates 1, 2 and 3 extend across the car from 95 side to side and are formed with integral flanges 4 along the vertical edges which overlap and are secured to the frame members

of the side walls 5 of the car by any suitable means.

The top edge of the end wall is secured beneath the fascia boards 7 and the meeting edges of the plates overlap and are secured together by rows of rivets 8 and the lower edge of the end wall is secured to the end sill 9. Nailing strips 10 are secured to the plates 1, 2 and 3 by bolts and lining 11 is secured to the nailing strips 10.

Figs. 3 and 4 show the invention applied to a gondola type of car, wherein only one plate 12 is used to form the end panel which extends from side to side of the car and is provided along the vertical edges with flanges 13 which overlap and are secured to the frame members of the side walls 14 by any suitable means. The top edge of the plate is secured to the top chord 15 by rivets 16, while the lower edge is secured by rivets 17 to the end sill 18.

While the corrugations are shown pressed outwardly, and in horizontal arrangement, it is understood that the corrugations may be pressed inwardly, or partially inwardly and partially outwardly from the original plane of the plate or the corrugations may be placed in any position, for instance, vertically or diagonally. The plates or panels may be positioned vertically or horizontally and applied to any type of railway car.

Fig. 5 to 9 inclusive show the preferred form wherein the plate 30 is provided with a plurality of major corrugations 31 with preferably flat apices 36 which are spaced apart distances substantially equal to their respective widths and the parts 33 of the plate between the major corrugations are also preferably flat so that the configuration is symmetrical in cross section about a line midway between the outermost portions of these major corrugations, which line is the neutral axis of the section. Such a section is very strong on account of the amount of metal positioned away from the neutral axis and is also relatively rigid. These major corrugations 31 are preferably widest adjacent their middle portion and decrease in width toward their opposite ends, and the apices change from a flat to an arcuate configuration. The metallic plate is also provided with a plurality of a aligned minor corrugations 32 which lie between adjacent major corrugations 31 with their inner ends preferably terminating into the plate adjacent each other and with their outer ends terminating into the plate in line with the outer ends of the major corrugations.

The outer ends of the minor corrugations 32 have arcuate apices and the parts of the plate between these outer ends of the minor corrugations and the outer ends of the major corrugations are also arcuate so that they form a cross section of sinuous configuration, and, furthermore, the outer ends of the minor

and major corrugations are of the same width and spaced apart distances substantially equal to their respective widths so that they form a contiguous sinuous configuration symmetrical in cross section about a line midway between the outermost portions of the corrugations, which line is the neutral axis of the section. Such a section is very resilient and has a spring like action under load, and, furthermore, produces a very strong section for the amount of metal used. The minor and major corrugations merge into the plane of the plate by means of terminal portions 46 of any desired formation. By such an arrangement a corrugated metallic plate is provided which is relatively rigid adjacent the middle of the plate and relatively resilient adjacent the opposite end portions of the corrugations.

Figs. 16, 17 and 18 are detail enlargements of portions of the plate taken on lines 7, 8 and 9, respectively, of Fig. 5, showing the flat apex 36 of the major corrugations (Fig. 16) and the contiguous sinuous configuration of the major and minor corrugations 31—32 (Fig. 18).

Figs. 10, 11 and 12 are detail enlargements of a modified form of corrugation similar to Figs. 16, 17 and 18, respectively, wherein the apex 40 of the major corrugation is arcuate, while Figs. 13, 14 and 15 show both the major and minor corrugations having flat apices.

The major corrugations are preferably of uniform width for a short distance adjacent their middle to provide greater strength for a greater portion of the plate and also to facilitate the changing of the forming dies when it is desired to increase or decrease the length of the corrugations or embossments.

Plates provided with a plurality of contiguous narrow corrugations possess a considerable amount of elasticity and when struck a blow deflect readily and regain their shape without distortion, whereas a plate provided with wide flat corrugations, though better able to carry quiescent loads, has not the resiliency of the former and is more readily distorted when struck a blow.

It is, therefore, desirable to design a plate that possesses great strength to withstand the sudden impact loads or blows with sufficient resiliency to resist distortion.

This application is confined to the construction wherein the minor corrugations are positioned between the major corrugations, while my co-pending application Serial No. 595,682, filed October 19, 1922, for corrugated metallic wall elements covers the construction wherein the middle portion of the major corrugation is split into two or more minor corrugations.

This is a division of my co-pending application Serial No. 595,684, filed October 19, 1922.

The accompanying drawings illustrate the preferred form of the invention, though it

is to be understood that the invention is not to be limited to the exact details of construction shown and described, as it is obvious that various modifications thereof within the scope 5 of the claims will occur to persons skilled in the art.

I claim:

1. A metallic plate provided with a plurality of parallel major corrugations whose 10 width is greatest at the center decreasing in width towards the terminal thereof adjacent the edges of said plate, a plurality of minor corrugations lying in a plane between said major corrugations, said minor corrugations 15 merging from the plane of said plate adjacent the center thereof and increasing in width and depth towards the terminals adjacent the edges of said plate.

2. A metal plate provided with a plurality 20 of major and minor corrugations, said major corrugations projecting from the original plane of said plate forming a uniform cross section at the center thereof with flat apices of greater width at the center and diminishing 25 in width towards the end of said corrugations where said major and minor corrugations merge and become contiguous and of a sinuous formation.

3. A metallic plate having a plurality of 30 major and minor corrugations, terminating within the plate, said major corrugations formed with flat apices decreasing in width from the center toward the ends of said corrugations, said minor corrugations positioned 35 between said major corrugations merging from substantially the center and the plane of the plate, and increasing in depth and width until they merge with said major corrugations to form a truncated contiguous configuration of uniform cross sections.

4. A metallic plate having a plurality of major and minor stiffening corrugations of 40 varying cross sections throughout the greater portion of their length, said minor corrugations merging into the plate adjacent the center of the major corrugations forming a cross section uniform in depth, width and shape symmetrical about a line midway between the outermost portions of the corrugations.

5. A sheet metal provided with a plurality 50 of major and minor corrugations, said major corrugations being widest, contiguous and symmetrical and provided with flat apices of greatest width adjacent the center, diminishing 55 in width toward the end of said corrugation where said major and minor corrugations merge and become contiguous, symmetrical and parallel for a short distance just before merging into the original plane of the plate.

6. A metallic plate having a plurality of 60 truncated major and minor corrugations terminating within the plate, said major corrugations decreasing in width from the center toward the ends, said minor corrugations 65 positioned between said major corrugations

merging from substantially the center and the plane of the plate and increasing in depth and width until they merge with said major corrugations to form a truncated contiguous configuration of uniform cross section. 70

7. A metallic plate having a plurality of 75 sinuous and contiguous major and minor corrugations terminating within the plate, said major corrugations decreasing in width from the center toward the ends, said minor corrugations positioned between said major corrugations merging from substantially the center and the plane of the plate and increasing in depth and width until they merge with 80 said major corrugations to form a sinuous and contiguous configuration of uniform cross section.

8. A metallic plate having a plurality of 85 major and minor corrugations terminating within the plate, said major corrugations being parallel, contiguous, symmetrical and widest adjacent their center and diminishing in width toward their ends, said minor corrugations positioned between said major corrugations merging substantially from the 90 center and the plane of the plate, and increasing in depth and width until they merge with said major corrugations to form a contiguous configuration of uniform cross section.

9. A metallic plate having a plurality of 95 major and minor corrugations terminating within the plate, said major corrugations decreasing in width from the center toward their ends, said minor corrugations positioned between the major corrugations merging from substantially the center and the plane of the plate, and increasing in depth and width until they merge with the major corrugations to form a contiguous configuration of uniform cross section. 100

10. A metallic plate provided with a plurality of major corrugations spaced apart intermediate their ends distances equal to their width which decrease in width toward their ends, and a plurality of minor corrugations 110 lying substantially between said major corrugations which increase in width toward the edges of the plate until said major and minor corrugations adjacent their ends are spaced apart distances equal to their width. 115

11. A metallic plate provided with a plurality of major corrugations symmetrical in cross section about a line midway between the outermost portions of the corrugations which decrease in width toward their ends, and a 120 plurality of minor corrugations lying substantially between said major corrugations which increase in width toward the edges of the plate until they form a cross section symmetrical about a line midway between the 125 outermost portions of the corrugations.

12. A metallic plate provided with a plurality of minor corrugations lying substantially between wider and deeper major corrugations, the length of the center line of the 130

metal of a cross section of the major corrugations adjacent the middle of the plate being the same as the length of the metal of a cross section of the major and minor corrugations 5 adjacent the edge of the plate.

13. A metallic plate provided with a plurality of major corrugations having substantially flat apices which decrease in width toward their ends, and a plurality of minor 10 corrugations lying substantially between said major corrugations which increase in width toward the edges of the plate, said major and minor corrugations being contiguous adjacent their ends and forming a sinuous configuration. 15

14. A metallic plate provided with a plurality of major corrugations which decrease in width toward their ends, and a pair of aligned minor corrugations positioned substantially between adjacent major corrugations with their inner ends terminating into the plate and with their outer ends terminating into the plate in line with the outer ends of the major corrugations, said minor corrugations increasing in width toward their outer ends. 25

15. A wall for a railway car comprising a metallic plate secured to oppositely disposed frame members of the car, said plate provided 30 with a plurality of major corrugations which decrease in width toward their ends, said plate also provided with a plurality of minor corrugations lying substantially between said major corrugations which increase in width 35 toward the edges of the plate until the major and minor corrugations terminate into the plate adjacent said oppositely disposed frame members. 45

16. A wall for a railway car comprising a metallic plate secured to oppositely disposed 40 frame members of the car, said plate provided with a plurality of major corrugations spaced apart intermediate their ends distances substantially equal to their width which decrease 45 in width toward their ends, said plate also provided with a plurality of minor corrugations lying substantially between said major corrugations which increase in width toward the edges of the plate until the major and 50 minor corrugations are spaced apart distances equal to their width adjacent said oppositely disposed frame members. 55

17. A wall for a railway car comprising a metallic plate secured to oppositely disposed 55 frame members of the car, said plate provided with a plurality of major corrugations symmetrical in cross section about a line midway between the outermost portions of the corrugations which decrease in width toward 60 their ends, said plate also provided with a plurality of minor corrugations lying substantially between said major corrugations which increase in width toward the edges of the plate until the major and minor corrugations form a cross section symmetrical about 65

a line midway between the outermost portions of the corrugations, adjacent said oppositely disposed frame members. 70

18. A wall for a railway car comprising a metallic plate secured to oppositely disposed frame members of the car, said plate provided with a plurality of major corrugations which decrease in width toward their ends, said plate also provided with a plurality of minor corrugations lying substantially between said major corrugations which increase in width toward the edges of the plate adjacent said oppositely disposed frame members, the length of the center line of the metal of a cross section of the major corrugations adjacent the middle 80 of the plate being the same as the length of the center line of the metal of a cross section of the major and minor corrugations adjacent said oppositely disposed frame members. 85

19. A wall for a railway car comprising a metallic plate secured to oppositely disposed frame members of the car, said plate provided with a plurality of truncated major corrugations which decrease in width toward their ends, said plate also provided with a plurality of minor corrugations lying substantially between said major corrugations which increase in width toward the edges of the plate until the major and minor corrugations are contiguous and form a sinuous configuration 95 adjacent said oppositely disposed frame members. 100

20. A metallic plate provided with a plurality of major corrugations which decrease in width toward their ends, said plate also provided with a plurality of minor corrugations lying substantially between said major corrugations which increase in width toward their outer ends and terminate into the plate substantially in alignment with the major 105 corrugations. 110

21. A metallic plate provided with a plurality of major corrugations spaced apart intermediate their ends distances substantially equal to their width which decrease in width toward their ends, said plate also provided with a plurality of minor corrugations lying substantially between said major corrugations which increase in width toward the edges of the plate until the major and minor corrugations are spaced apart distances equal to their width. 115

22. A metallic plate provided with a plurality of major corrugations symmetrical in cross section about a line midway between the outermost portions of the corrugations which decrease in width toward their ends, said plate also provided with a plurality of minor corrugations lying substantially between said major corrugations which increase in width toward the edges of the plate until the major and minor corrugations form a cross section symmetrical about a line midway between the outermost portions of the corrugations. 120 125 130

23. A metallic plate provided with a plurality of major corrugations which decrease in width toward their ends, said plate also provided with a plurality of minor corrugations lying substantially between said major corrugations which increase in width toward the edges of the plate, the length of the center line of the metal of a cross section of the major corrugations adjacent the middle of the plate being the same as the length of the center line of the metal of a cross section of the major and minor corrugations adjacent the edge of the plate. 65
24. A metallic plate provided with a plurality of truncated major corrugations which decrease in width toward their ends, said plate also provided with a plurality of minor corrugations lying substantially between said major corrugations which increase in width 70 toward the edges of the plate until the major and minor corrugations are contiguous and form a sinuous configuration. 80
25. A metallic plate provided with a plurality of major embossments having flat apices with the parts of the plate between the embossments also substantially flat, said plate also provided with a plurality of minor embossments lying substantially between the major embossments, which terminate into the plate substantially in alinement with the major embossments where the major and minor embossments have arcuate apices and the parts of the plate between the ends of the major and minor embossments are also of 85 arcuate configuration. 90
26. A metallic plate provided with a plurality of major embossments having flat apices with the parts of the plate between the embossments also substantially flat, said major embossments decreasing in width toward their opposite ends, said plate also provided with a plurality of minor embossments lying substantially between the major embossments which increase in width toward their outer 95 ends and terminate into the plate, substantially in alinement with the major embossments where the major and minor embossments have arcuate apices and the parts of the plate between the ends of the major and minor embossments are also of arcuate configuration. 100
27. A structure for a railway car comprising a metallic plate secured to oppositely disposed frame members of the car, said plate provided with a plurality of major embossments having flat apices with the parts of the plate between the embossments also substantially flat, said plate also provided with a plurality of minor embossments lying substantially between the major embossments which terminate into the plate adjacent said oppositely disposed frame members where the major and minor embossments have arcuate apices and the parts of the plate be- 110
- tween the ends of the major and minor embossments are also of arcuate configuration. 115
28. A structure for a railway car comprising a metallic plate secured to oppositely disposed frame members of the car, said plate provided with a plurality of major embossments having flat apices with the parts of the plate between the embossments also substantially flat, said major embossments decreasing in width toward their opposite ends, said plate also provided with a plurality of minor embossments lying substantially between the major embossments which increase in width and terminate into the plate adjacent said oppositely disposed frame members where the major and minor embossments have arcuate apices and the parts of the plate between the ends of the major and minor embossments are also of arcuate configuration. 120
29. A metallic structure for a railway car, comprising a metallic plate secured to oppositely disposed vertical frame members of the structure, said plate provided with a plurality of constant depth, horizontal major corrugations with substantially flat apices with the parts of the plate between the major corrugations also substantially flat, said plate also provided with a plurality of minor corrugations lying substantially between the major corrugations which terminate into the plate adjacent said frame members substantially in alinement with said major corrugations where the major and minor corrugations have arcuate apices and the parts of the plate between the ends of the major and minor corrugations are also of arcuate configuration. 125
30. A metallic plate provided with a plurality of major corrugations and a pair of aligned minor corrugations positioned between adjacent major corrugations with their inner ends terminating into the plate and with their outer ends terminating into the plate in line with the outer ends of the major corrugations. 130
31. A wall for a railway car comprising a metallic plate secured to oppositely disposed frame members of the car provided with a plurality of major corrugations which terminate into the plate adjacent said frame members, and a pair of aligned minor corrugations positioned between adjacent major corrugations with their inner ends terminating into the plate and with their outer ends terminating into the plate in line with the outer ends of the major corrugations. 135
32. A wall structure for a railway car comprising a metallic plate secured to oppositely disposed frame members of the car provided with a plurality of varying width major corrugations and a pair of aligned varying width minor corrugations positioned between adjacent major corrugations, the outer ends of the major and minor corrugations terminating within the plate substantially in alinement. 140

with each other adjacent said frame members, the maximum strength of the corrugated wall being substantially midway between the frame member.

33. A metallic plate provided with a plurality of varying width major corrugations and a pair of aligned varying width minor corrugations positioned between adjacent

major corrugations, the outer ends of the major and minor corrugations terminating within the plate substantially in alinement with each other, the maximum strength of the corrugated wall being adjacent the middle of the major corrugations. 10

ARTHUR E. SMALL.
